UNITED STATES PATENT OFFICE.

ARTHUR SPEAR, DECEASED, LATE OF BROOKLYN, NEW YORK, BY MYRTLE B. SPEAR,
EXECUTRIX, OF BROOKLYN, NEW YORK.

SPEED CHANGING AND CONTROLLING DEVICE.

1,223,436.

Specification of Letters Patent.

Patented Apr. 24, 1917.

Application filed November 10, 1914. Serial No. 871,397.

To all whom it may concern:

Be it known that ARTHUR SPEAR, deceased, late a citizen of the United States and resident of Brooklyn, in the county of Kings and State of New York, did invent new and useful Improvements in Speed Changing and Controlling Devices, of which the following is a specification.

The invention relates to devices and improvements for controlling the change speed gear or mechanism in which a transmission or like mechanism is interposed between the engine and the driven part to vary their relative speed or direction, as in automobiles or like machines.

In many of its aspects the invention is an improvement or modification of that shown in U. S. Patent No. 1,121,413, dated Dec. 15, 1914, the application for which was copending herewith. The objects and advantages of the invention in part will be found in said application, and in part will be set forth hereinafter or will be obvious herefrom.

The invention consists in the novel parts, mechanisms, combinations, arrangements, improvements and instrumentalities herein shown and described.

The accompanying drawing, referred to herein and forming a part hereof, illustrate one embodiment of the invention, the same serving in connection with the description herein to explain the principles of the invention.

Of the drawings

Figure 1 is a view, largely diagrammatic, of the present invention, said figure corresponding largely to Fig. 11 of said prior application and

Fig. 2 is a fragmentary plan, partly diagrammatic corresponding generally to Fig. 1 of said application.

Fig. 3 is a top plan of the controlling slides, partially withdrawn from their mounting, with associated parts;

Fig. 4 is an elevation looking at Fig. 3 from the bottom;

Fig. 5 is an elevation looking at Fig. 3 from the right side;

Fig. 6 is a fragmentary plan of the gear shifting rods, showing the relation thereto of the actuating arm;

Fig. 7 is a detail of the actuating slides; and

Fig. 8 is a side elevation, partly diagrammatic, of parts of the shifting mechanism. 55

Referring in detail to the exemplification embodied in the drawing, the rod or arm 10 is the same as that to the correspondingly numbered 10 and shown in Figs. 1, 3, 6 and 11 of Patent No. 1,121,413 previously referred to. This arm 10, as explained in said patent, is adapted to move into and out of operative or actuating positions with reference to any one of a plurality of gear shifting members, and to move them into or out of operative relation to determine the speed or ratio of rotation of the engine relative to the driven wheels and also to determine the direction of the rotation. The arm 10 for the purposes of this application is mounted in the same manner and has the same movement as the arm 10 in said patent. 70

Referring to the accompanying drawings, illustrating by way of example one embodiment of the invention, the same is shown applied to a well known type of speed changing device in which the gears are shifted into and out of engagement to effect the requisite and desired changes in speed. 75 The particular mechanism of the transmission is not illustrated in detail, but is shown inclosed in a casing 1. The gears are shifted in effecting the speed changes by means of movable members shown herein as sliding rods 2, 3 and 4. These rods are connected to the slideable or shiftable gears within the casing 1 to slide or shift them to and fro as may be necessary to effect the speed changes. 85

The movable slideable members or rods 2, 3 and 4 are located side by side so that their moving device, such as the arm 10, may pass from one to the other and are each provided with means adapted to be engaged by such selecting and moving means adapted to move or slide any selected one of said members to and fro for the purpose stated. Said moving means is constructed so that it may move into operative relation with either 95 one of the slideable members or rods, and from one to the other of them so as to select 100

the proper or desired rod and to then move it in the desired direction.

The embodied form of engaging device on the slidable rods comprises two parallel lugs 5 or lips 5 and 6 between which the actuating device therefor slides from one of the rods 2, 3 and 4 to another, and against which said device presses in sliding the rods, in one direction or the other. These engaging devices 5 and 6 are in alinement with each other, as shown in Fig. 6, when the moving means therefor is in what for convenience of language may be termed the initial or neutral position.

15 There is provided by my invention means operating automatically under the control of suitable settable devices for moving or sliding the rods 2, 3 and 4 to effect the desired changes in speed, and which automatically 20 pass into and out of engagement with the various rods as desired, but it will be understood that so far as concerns many aspects of the invention, said automatic actuating means is adapted to operate with gear actuating connections other than slidable rods.

The moving device which coöperates directly with the slidable rods 2, 3 and 4 in the present embodiment comprises an arm 10 mounted to slide and also to rock on a shaft 30 11 carried on a suitable support such as brackets 12 and 13, the end of said arm 10 engaging slidable rods 2, 3 and 4 between the lugs 5 and 6. As embodied the rocking movement carries the arm from one slide to 35 another and the sliding movement of arm 10 on its support 11 effects the sliding movement of rods 2, 3 and 4.

The automatic devices which in the embodied form effect the selecting action, that 40 is, move the arm 10 into engagement with one of the slidable rods or the other thereof and which then move the arm and selected rod to effect the gear change are located just above or adjacent to said slidable rods as

45 best appears from Fig. 2, and comprises a plurality of guiding and actuating members moving relatively to each other and adapted to move the arm 10 and thereby the slidable rods 2, 3 and 4. There is also provided a 50 suitable handle 14 fixed to arm 10, if desired, by which the speed changes may be manually effected. As embodied, said automatic devices comprise guiding and actuating means. The guiding means as embodied 55 comprises a fixed guide plate 15 (see especially Figs. 1 and 3) provided with guiding means in the form of an opening 16 through which the arm 10 passes, the opening 16 being so shaped that the arm 10 will always 60 move in the right direction to effect the speed change or gear shift desired. (This relation of the parts is shown in Fig. 2). In such embodied form it is suited for a machine having four speed changes, together 65 with the reverse and the initial position.

The arm 10 travels in the opening or slot 16. Coöperating with said arm and guiding means are the actuating means, comprising a plurality of actuators, which in accordance with certain features of the invention are 70 successively actuatable. That is, one actuator operates in conjunction with the guiding means and then another to give the requisite throw out of one gear connection and the throwing in of another. In certain aspects of the invention also they are electrically operated. In the embodied form said means comprises a plurality of slides each having an opening therein through which the arm 10 also passes as well as through the 80 guide plate. The openings in said guide slides are formed so that in coöperation with the guide plate and being operated or actuated in proper sequence, the shift of the gears from one speed to another is effected 85 through the movement of arm 10.

The staff 10 in the portion 17 of slot 16 travels to and fro in what, for convenience of language, may be termed the transverse direction whereby it passes into or out of 90 engagement with any one of the rods 2, 3 or 4, as desired, during which movement it rocks upon the shaft 11. It also travels in what for convenience of language may be termed the longitudinal direction into and 95 out of slots 18, 19, 20, 21 or 22, during which movement it slides on shaft 11. It will thus be seen that in passing from one position of the slidable rods and of the gears to another position thereof, the arm 10 must 100 return to or pass through the slot 17, which corresponds to the initial position and to the neutral or initial position for the gear shift. It will be also understood that the movable members or slidable rods move to and from the initial position at which the arm 10 passes into or out of operation with a particular movable member or slidable rod, as 105 desired.

In the embodied form of means are provided also actuating and guiding members coöperating with the foregoing instrumentalities, and with the embodied form thereof for effecting the desired movements of the arm 10, these guiding and actuating members being actuated and controlled from settable means, which are set by the operator for the desired position of the speed changing devices or of the gears. In accordance with certain features of the invention these 110 guiding and moving members are actuated by magnetic means as provided by certain features of the invention. In the embodied form said means comprises a plurality of slidable plates already briefly referred to, 115 said plates work in close proximity to the fixed guide plate 15. In the embodied form said guiding and moving plates are three in number and are designated by reference numerals 25, 26 and 27 and are slidable in 120 125 130

guide ways formed in the support for fixed plate 15 (see Figs. 3, 4 and 5). These guiding and moving slides, as well as the guide plate 15 in the present embodiment are designed to give four speeds forward and the reverse in addition to the initial or disengaged position, and the particular conformation and construction thereof will be described in connection with the speed changing capacity or capability just mentioned. The slidable plate 26 is shown with a transverse slot 30 therein, which permits of relative movement of the arm 10 with respect to the slide 26 transversely, but the slide 26 and the arm 10 traveling together longitudinally, using those terms in the same sense of direction in which the plate 26 slides.

By consideration of the foregoing description and the drawings herewith, and referring especially to Figs. 2 and 4 of the drawings, it will be understood that the slide 26 with its transverse slot 30 is adapted to move the arm 10 into and out of each of the slots 18, 19, 20, 21 or 22 and to restore it to the initial position, that is, in the slot 17.

The sliding plate 25 has an opening 131 therein rectangular at the end 132 thereof, and diamond shaped at the end 133. The sliding plate 27 is provided with a diamond shaped opening 134 (see especially Fig. 7).

As embodied, the guide plate 15 is mounted above the actuator slides 25, 26 and 27, and all these are carried on a suitable supporting frame 151 just over the sliding rods 2, 3 and 4. The guide 15 is fixed upon said frame 151 and the actuators 25, 26 and 27 slide in grooves therein. These are arranged just under or in line with the mounting 11 for arm 10 (see Figs. 1, 2, 3 and 8), so that the arm 10 can pass through the guide plate and actuators and engage with the slidable rods 2, 3 and 4 and pass from one to the other and move any desired rod to and fro.

As a matter of convenience of illustration in Figs. 3 and 4 the slides are shown almost totally withdrawn from their mountings, but it will be understood that in the embodied device when assembled the arm 10 passes through each of these openings, as appears from Figs. 1 and 2 of the drawings.

In accordance with certain aspects of the present invention, electrically or electromagnetically operated actuating means for the gear-shifting devices are provided, and in accordance with one feature of the invention said devices are automatically operated by selectively settable circuit opening and closing devices, the electrical operating means operating to make the desired shift in the gears, and also preliminarily thereto throwing out the engine clutch and throwing it in again after the shifting has been accomplished. It will be understood that, in certain aspects of the invention, the initial

throwing out of the engine clutch and the subsequent or sequential throwing in thereof is automatic and all that is required of the driver is to press a button or other circuit controlling device corresponding to the speed desired irrespective of whichever speed may have been previously or precedingly used.

In the embodied form, solenoids are employed for sliding the plates 25, 26 and 27, the current for the solenoids being obtained from a primary generator driven by the engine, (such as is widely used on motor cars at the present time), or from a secondary battery, with the utilization where desired or required of suitable current flow and current tension changing and controlling devices.

The slide 25 in the present case is connected by a rod 30 (from this point forward in the description there is no necessary correspondence between the reference numerals in this application and the copending application upon which Pat. No. 1,121,413 was issued) to a solenoid 31 adapted to move the slide 25 in one direction.

The slide 26 has connected thereto a rod 34 connected to the core of the solenoid 35, and at its opposite end, said slide 26 has a rod 36 attached thereto connected to the core of a solenoid 37.

The slide 27 at the left hand end has attached thereto a rod 38, connected to the core of a solenoid 39, and at its opposite end said slide has attached thereto a rod 40 connected to the core of a solenoid 41.

The centering of the core of one solenoid preferably decenters the core of the other solenoid connected to the same slide, which latter solenoid is dead at the time, and the entire mechanical energy produced is available to perform the desired work less inevitable friction.

In the embodied form of means for throwing out the clutch, a solenoid 45 is provided, which may be used to release the clutch just prior to the gear shift, said solenoid being used to release for action an actuating spring, the throwing in of the engine clutch after the shifting of the gear being effected by hand.

In the embodied form of engine clutch actuating device, a solenoid 45 has its core connected to a rod 46 which rod is pivotally connected to an arm 47 fixed to a rock shaft 48. Said rock shaft 48 is connected to a clutch actuating device 49 with which cooperates a spring 50. The engine is indicated by 51 and the fly wheel by 52.

A suitable brake actuating device is provided, in which a solenoid 55 has its core connected to a rock arm 57 upon the actuating shaft 58 of a band brake 59 operating on the hub of a wheel 60.

Referring to Fig. 1 the plate 15 has marked thereon the Figs. 1, 2 and 3 and the

letter "H" to indicate the successive one, second, third and highest forward speeds, and the letter "R" to indicate the reverse speed or direction, similarly to the copending application referred to.

As explained in said patent, the slotted plate 26, which is the same as the correspondingly numbered plate in that application, will move the arm 10 into and out of each of the longitudinal slots marked R, 1, 2, 3, and H, and the other two slides coöperating therewith will give the requisite transverse movements through the central transverse slot.

15 In connection with the circuits, and by way of further explanation, if it were desired to move from high to first speed, the switch or button marked "First" will close a circuit at 62 to throw out the engine clutch, 20 and then will close circuits at 63 and 64 to move slide 27 to the right and slide 26 downwardly in Fig. 1. As the key comes back it will open the circuit at 62 and the engine clutch will be thrown in again. So far as 25 concerns various features of the invention, as already indicated, the clutch throw out may be operated in some other manner. The other switches or keys and the other slides will operate in a similar manner as will be 30 clearly understood from the foregoing.

At 70 is indicated an electrical generator driven by the engine of the automobile, as is usual in connection with the lighting and starting systems used on motor cars. A secondary source of power may be used and any voltage and amperage changing devices as found necessary or advisable in any particular case.

The invention in its broader aspects, is 40 not limited to the particular construction shown, nor to any particular constructions by which it has been or may be carried into effect, as many changes may be made in the construction, within the scope of the accompanying claims without departing from the main principles of the invention and without 45 sacrificing its chief advantages.

What is claimed as the invention and desired to be secured by Letters Patent is:—

- 50 1. A speed changing and controlling device including in combination a plurality of selectively coöperating movable devices for effecting the various gear shifts, separate electrical operating means including a plurality of circuits for moving the various coöperating devices, and circuit controlling means for selectively controlling one or more of said circuits to effect a desired gear shift.
- 55 2. A speed changing and controlling device including in combination a plurality of selectively coöperating movable devices for effecting the various gear shifts, separate

electro-magnetic means including a plurality of circuits for moving the various coöperating devices, and circuit controlling means 65 for selectively controlling one or more of said circuits to effect a desired gear shift.

3. A speed changing and controlling device including in combination a plurality of selectively coöperating slidable members for 70 effecting the various gear shifts, solenoids for operating the various slidable members, circuits for said solenoids, and circuit controlling means opening and closing one or more of said circuits for effecting a desired 75 gear shift.

4. A speed changing and controlling device including in combination a plurality of selectively coöperating successively movable devices for effecting the various gear shifts, 80 separate electrical operating means including a plurality of circuits for moving the various coöperating devices, and circuit controlling means for selectively controlling one or more of said circuits to sequentially effect 85 a desired gear shift.

5. A speed changing and controlling device including in combination a plurality of selectively coöperating slidable members for effecting the various gear shifts, solenoids for operating the various slidable members, circuits for said solenoids, and circuit controlling means opening and closing successively a plurality of circuits to sequentially operate a plurality of solenoids 95 to effect a desired gear shift.

6. A speed changing and controlling device including in combination an electrically operated engine clutch control and a circuit therefor, an electrically operated gear shifting device and a circuit therefor, and a single circuit opening and closing switch sequentially controlling said two circuits upon a single actuation.

7. A speed changing and controlling device including in combination an electrically operated engine clutch control and a circuit therefor, an electrically operated gear shifting device comprising a plurality of successively coöperating electrically operated members and circuits therefor, and circuit controlling devices corresponding to the various gear shifts, said circuit controlling devices successively affecting the clutch circuit and then one or more of the other circuits as may 110 be required for the particular shift desired.

In testimony whereof, I have signed my name to this specification in the presence of two subscribing witnesses.
